UNITED STATES PATENT OFFICE

2,372,851

APPARATUS FOR GAMES OR THE LIKE

James M. Prentice, South Hadley, Mass.

Application March 20, 1944, Serial No. 527,158

2 Claims. (Cl. 273—138)

This invention relates to improvements in indicating apparatus and is directed more particularly to apparatus for indicating results.

The principal objects of the invention are directed to the provision of apparatus wherein a plurality of prime members and a secondary member are interconnected for relative movements in such a way that as one or both of the prime members are moved the secondary member is moved thereby.

The invention is adapted for broad application but for purposes of description the invention will be described in connection with game apparatus.

Various novel features of construction and the advantages of the invention will be observed from the following description thereof with reference to the drawings, wherein:

Fig. 1 is a top plan view of a game apparatus embodying the novel features of the invention;

Fig. 2 is a bottom plan view of the apparatus shown in Fig. 1 with the lower panel removed;

Fig. 3 is a sectional elevational view on the line 3—3 of Fig. 2; and

Figs. 4 and 5 are top and bottom plan views similar to Figs. 1 and 2 showing a modified form of the invention.

Referring now to the drawings more in detail, the invention will be fully described. It will be understood that while the invention is to be described in connection with game apparatus that it is not to be so limited since the invention is adapted for various uses in connection with various forms of the apparatus.

As in Fig. 1, an upper game board or panel is represented by 2 which preferably has a frame 4 therearound. The board 2 may be arranged for any game desired. As an illustration where the game is a football game the board may be ornamented with matter appropriate to that kind of a game. A lower panel 3 is omitted in Fig. 2.

A result window is provided at 6 and play windows 8 and 10 are provided as shown. These may be called prime windows. A member 12 is movable below the window 6 and other members 14 and 16 are movable below the windows 8 and 10.

In the play of a game the window 8 may be for a player or set of players and the window 10 may be for an opposing player or an opposing set of players.

The movable members 14 and 16 may carry characters as in the case of a football game, a set of different plays. The players or sets of players in their turn according to the rules of

play move the said movable members 14 and 16 to position certain plays in the windows 8 and 10.

Obviously the rules of the game may be varied within wide limits and for purposes of description it is of no consequence whether the players move the carrier members 14 and 16 so as to position a certain play at the windows 8 and 10 or they are required to move said members in a certain way so that an unknown play is positioned at the windows. Each of the members 14 and 16 carry a plurality of plays as stated and those on one may include "tackle" and those on the other may include "forward pass."

The result member 12 carries a plurality of results and as will hereinafter be described the said member 12 is moved accordingly as the members 14 and 16 are moved so as to position a certain result at window 6. For instance among the results may be "5 yd. gain." The plays and results may be so arranged on their respective carriers that a result will be presented to result window 6 which is more or less normal relative to the plays presented at the play windows.

The movable member 12 may take the form of a disc as shown which has a shaft 20 suitably journaled for rotation. The members 14 and 16 are arranged for sliding movements in guideways formed by the sides of the frame 4, panel 2 and members 22.

25 A rack 24 meshes with a pinion 26 which is fixed to the member 12 or the shaft 20 and it is guided for reciprocating movements in a guideway 28. If desired, the member 24 may carry results and the member 12 be eliminated, so that 24 will be the result member.

Shafts 30 and 32 are journaled for rotation relative to the panel 2 and carry manually engageable members 34 outside or on top of panel 2 and pinions 36 which mesh with teeth provided on the members 14 and 16, as shown.

40 A bar member 38 is pivoted at 40 to the member 24 in any suitable manner as to a block 42 secured to the member 24. Opposite ends of the bar 38 are slotted to receive pins 44 on the carriers 14 and 16, as shown.

The members 14 and 16 and their respective guideways are so arranged that said members 14 and 16 are frictionally engaged so that as one of the carriers is moved, the other will be frictionally held against movement whereby the pin 44 of the carrier so held functions as a pivot for the bar 38. Said bar having its other end moved by a carrier the member 24 is moved to rotate member 12.

50 Thus one of the carriers 14 or 16 is moved

so as to bring about movement of carrier 12 to present a result to the window 6. Then the other carrier is moved and a different result may be presented to the result window.

A slide 50 is provided to cover the window 6 and it has a stem 52 slideable in the frame 4 with a spring 54 around the stem between said frame and slide. A manually engageable member 56 is provided on the stem 52. This may be grasped by the fingers of the hand for moving the slide against the spring to uncover the window.

According to the invention shown in Figs. 4 and 5, a top panel 60 has a result window 62 and play panels 64 and 66 which correspond to the windows previously described.

Carriers 70 and 72 have portions 74 and 76 that are slideable in guideways between the panel 60 and guide members 78. The guideways as before described are arranged for frictionally engaging the slideable members for the purpose already described.

A result carrier 78' has a shaft 80 journalled for rotation relative to the panel 60 and said shaft carries a grooved pulley 82. A slide which may be in the form of a pin 86 is slideable in a guideway 88 and a bar 90 is journalled on the said pin 86.

Grooved idler wheels 92 are journalled on studs 94 and other wheels 96 are journalled on studs 98. A grooved idler wheel 100 is journalled at 102. Opposite ends of the bar 90 are slotted and receive pins 103 of the carriers 70 and 72.

A flexible member represented by 104 has its opposite ends fixed to the carrier 70 and it passes around the wheels 92 and 96 as shown. A similar member 106 has its opposite ends fixed to carrier 72 and it passes around wheels 92 and 96. There may be several wraps of the members 104 and 106 around the wheels 96 to which wheels the said members may be fastened if desired.

A flexible member 108 has opposite ends fixed to the connection 86 and it passes around the idler 100 and the wheel 82.

With the carriers 70 and 72 in frictional engagement with their respective guideways one of the carriers may be moved to position a play at one of the play windows and accordingly as the carriers are moved the result member will be moved thereby.

The carriers 70 and 72 may be moved by various means but as a suitable means manually engageable members 106 fixed to the said carriers extend through slots 108 in the panel 60.

Thus the prime members or carriers which carry plays or prime characters are independently movable to present prime characters to their respective windows. Being operably connected to the result member said member is actuated accordingly as the prime members are moved.

The invention may be embodied in other specific forms without departing from the essential characteristics thereof. Hence, the present embodiments are therefore to be considered in all

respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. As a new article of manufacture, a game apparatus comprising in combination, a supporting structure including a panel provided with a result window and separate play windows, a result member carrying results mounted for rotation in said structure beneath said panel whereby results thereon may register with the result window, carrier members reciprocably and frictionally mounted beneath said panel carrying indicia representing plays for registering with the play windows, an operating member reciprocable in said structure and operative means connecting it to said result member whereby the latter may be rotated by reciprocation of the former, means for reciprocating said carrier members, a lever pivoted intermediate its ends to said reciprocable member, connections between opposite ends of said lever and said carrier members, all adapted and arranged whereby one of said carrier members may be reciprocated while the other carrier member is frictionally held against reciprocation thereby to actuate the operating member and bring about rotation of the result member or both of said carrier members may be reciprocated to rotate the result member.

2. As a new article of manufacture, a game apparatus comprising in combination, a supporting structure including a panel provided with a result window and separate play windows, a result member carrying results mounted for rotation in said structure beneath said panel whereby results thereon may register with the result window, carrier members reciprocably and frictionally mounted beneath said panel carrying indicia representing plays for registering with the play windows, an operating member reciprocable in said structure and operative means connecting it to said result member whereby the latter may be rotated by reciprocation of the former, means for reciprocating said carrier members, a lever pivoted intermediate its ends to said reciprocable member, connections between opposite ends of said lever and said carrier members, all adapted and arranged whereby one of said carrier members may be reciprocated while the other carrier member is frictionally held against reciprocation thereby to actuate the operating member and bring about rotation of the result member or both of said carrier members may be reciprocated to rotate the result member, and a slide reciprocable relative to said panel adapted to close the result window.

JAMES M. PRENTICE.
